UNITED STATES PATENT OFFICE.

HERMAN IHLENBURG, OF PHILADELPHIA, PA., ASSIGNOR TO DAVID WOLFE BRUCE, OF NEW YORK, N. Y.

DESIGN FOR FONT OF PRINTING-TYPE.

SPECIFICATION forming part of Design No. 12,263, dated May 17, 1881.

Application filed April 6, 1881. Term of patent 14 years.

To all whom it may concern:

Be it known that I, HERMAN IHLENBURG, (assignor to DAVID WOLFE BRUCE,) of Philadelphia, in the county of Philadelphia, Pennsylvania, have invented and originated a new Design for a Font of Printing-Type, of which the following is a specification.

The nature of my design is clearly shown in the accompanying typographic impression, to 10 which reference is made; and it consists of a heavy letter, somewhat similar to the class known as "mediaeval," shaded upon the right and below by a lighter line. Upon the upper left-hand portion of the letters, except the C, 15 G, O, Q, and S, this light-shade line also occurs, and is curved, save in the letter M, in which a horizontal line is used. The lower left-hand termination of the A is ball-shaped. The upper right-hand terminations of the C, 20 F, and G are triangular, followed by the ball-termination. The upper and lower right-hand terminations of the E are triangular, followed by the ball-termination. The lower right-hand terminations of the L, M, and N are ball-shaped.

Both terminations of the S and Q are ball-shaped. Both the upper terminations of the T are ball-shaped.

In the letters A and U the left-hand portion gradually widens about centrally, and this characteristic is found in both the right-hand and 30 left-hand portions of the M, O, Q, V, and W, and in the right-hand portion of the N. In the symbol & this characteristic is also found, and the ball termination occurs on the right.

In the punctuation-marks and numerals and 35 dollar and pound marks the character of the design is preserved, the ball termination being found in the commas, the apostrophe, and the interrogation-mark, and in the numerals 2, 3, 5, 6, 7, 9, and dollar and pound marks.

Having now described my invention, I 40 claim—

The design for a font of printing-type, as described and shown.

HERMAN IHLENBURG.

In presence of—

CHASTOPH LATHREY,
CHRISTIAN SHUSTER.
